[57] CLAIM

The ornamental design for a combined video camera
and built-in audio mixing, as shown and described.

DESCRIPTION

FIG. 1 is a top front and right side perspective view of
a combined video camera and built-in audio mixing
showing my new design;

FIG. 2 is a left side perspective view thereof;

FIG. 3 is a front elevational view thereof;

FIG. 4 is a top plan view thereof;
FIG. 5 is a right side elevational view thereof shown at
a reduced scale;

FIG. 6 is a rear elevational view thereof;

FIG. 7 is a bottom plan view thereof; and,

FIG. 8 is a left side elevational view thereof shown at a
reduced scale.
